CLAIM

The ornamental design for a rifle scope with turret and magnification adjusting ring, as shown and described.

DESCRIPTION

FIG. 1 is a perspective view a rifle scope with turret and magnification adjusting ring, showing my new design;

FIG. 2 is a perspective view thereof;

FIG. 3 is a first side elevational view thereof;

FIG. 4 is a second side elevational view thereof;

FIG. 5 is front elevational view thereof, the view as shown is taken from the direction and viewpoint indicated at location 5—5;

FIG. 6 is rear elevational view thereof, the view as shown is taken from the direction and viewpoint indicated at location 6—6;

FIG. 7 is a top elevational view thereof; and,

FIG. 8 is bottom elevational view thereof.

The broken lines depict portions of the rifle scope with turret and magnification adjusting ring that form no part of the claimed design. The broken line structure depicted in FIG. 1 is only partially depicted in the FIG. 2 through 8 views.
